DESIGN.

—o—

S. SALOMON.

NECKSCARF.

Des.
No. 15,688.

Patented Jan. 6, 1885.

UNITED STATES PATENT OFFICE.

SIEGFRIED SALOMON, OF NEW YORK, N. Y., ASSIGNOR TO HERMAN BENDIX, OF SAME PLACE.

DESIGN FOR A NECKSCARF.

SPECIFICATION forming part of Design No. 15,688, dated January 6, 1885.

Application filed November 29, 1884. Term of patent 7 years.

To all whom it may concern:

Be it known that I, SIEGFRIED SALOMON, a citizen of the United States, residing at New York, in the county and State of New York, 5 have invented and produced a new and original Design for Neckscarfs, of which the following is a specification.

This design relates to neckties, scarfs, and analogous articles; and it consists in the disposition on the front surface of the scarf of a series of squares in rows presenting the appearance of plaited or basket work, each square being raised in the middle and having two of its opposite edges raised above the 10 edges of the adjoining squares, while its two remaining edges are depressed below the raised edges of the adjoining squares.

The accompanying drawing represents a face view of a neckscarf ornamented with 20 my design, and since the design is applicable to any and all shapes of scarfs, bows, and analogous articles of neck-wear it has not been deemed necessary to show more than one type of scarf in which my design is exemplified.

25 In the drawing, the letter A designates a neckband, and B is the front or body of a scarf, the shape or outline of which constitutes no part of my design. The front surface of the body of the scarf is ornamented by a series of squares, *a b*, which are arranged in 30 rows and have their centers slightly raised,

the two opposite edges of each square being raised above the edges of the adjoining squares, while its two remaining edges are depressed below the raised edges of the adjoining squares. In each of the squares *a*, for instance, the edges *c d* are raised above the edges of the adjoining squares, *b b*, while the edges *e f* are depressed below the raised edges of the adjoining squares. 35

The design set forth in the foregoing description presents the appearance of plaited or basket work, and rich and ornamental effects are produced thereby. 40

What I claim is—

The design for the front of a neckscarf or analogous article of neck-wear, consisting of a series of squares in rows, each square being raised in the middle and having two of its opposite edges raised above the edges of the 50 adjoining squares, while its two remaining edges are depressed below the edges of the adjoining squares, and the whole presenting the appearance of plaited or basket work, substantially as shown. 45

In testimony whereof I have hereunto set my hand and seal in the presence of two subscribing witnesses.

SIEGFRIED SALOMON. [L. S.]

Witnesses:

W. HAUFF,
E. F. KASTENHUBER.
